UNITED STATES PATENT OFFICE.

JOSEPH W. THOMPSON, OF SALEM, OHIO, ASSIGNOR OF ONE-HALF TO THE BUCKEYE ENGINE COMPANY, OF SAME PLACE.

STEAM-ENGINE GOVERNOR.

SPECIFICATION forming part of Letters Patent No. 310,479, dated January 6, 1885.

Application filed August 15, 1884. (No model.)

To all whom it may concern:

Be it known that I, JOSEPH W. THOMPSON, of Salem, in the county of Columbiana and State of Ohio, have invented certain new and 5 useful Improvements in Steam-Engine Governors, of which improvements the following is a specification.

My invention relates to centrifugal governors of the class in which the position of a 10 valve-operating eccentric relatively to the crank-line is varied by the movements of weights rotating with the crank-shaft under varying degrees of centrifugal force, to the end of effecting regulation of the speed of the engine by variations in the travel of the valve, 15 and consequently in the period of steam-admission, in accordance with variations in pressure or resistance, an instance of which class is exemplified in Reissued Letters Patent No. 20 8,433, granted and issued to myself and the Buckeye Engine Company, as my assignee, under date of September 24, 1878.

The object of my invention is to provide a 25 governor of such character of simple and inexpensive construction and ready application in which are embodied the features of an increased range of traverse of the weights, effective application of the centripetal action of the springs, capacity of adjustment of relative 30 static and dynamic friction, and convenient adaptability to operation in either direction of rotation of the crank-shaft.

The improvements claimed are hereinafter 35 fully set forth.

In the accompanying drawings, Figure 1 is 40 a face view of a governor embodying my invention, and Fig. 2 a transverse section through the same at the line $x x$ of Fig. 1.

In the practice of my invention the mechanism of the governor is supported on and carried by a wheel or disk, 1, which may either be the fly-wheel of the engine or a wheel separately secured upon the crank-shaft. The eccentric 2, by which movement is imparted 45 to the valve governing the admission and exhaust of steam to and from the cylinder of the engine, is formed with or secured to an arm, 3, which is pivoted to the wheel 1 in proper angular relation to the crank by a journal, 4, 50 secured to the arm 3, and mounted in a bearing, 28, on the wheel, the eccentric surround-

ing the shaft and having sufficient space in the internal opening through which the shaft passes to admit of the range of movement about the axis of the journal 4 requisite for 55 its adjustments in the operation of the governor. The angular position of the eccentric-pivot, the mean direction of the eccentric-rod being parallel with the center line of the engine, is either in accordance radially with or directly 60 opposite radially to the crank, the latter being proper when the valve admits steam by its movement from the end at which admission is to be effected in the manner of the ordinary slide-valve, and its direction of movement relatively to the eccentric is not reversed by intermediate gear. Under such conditions, and where the travel of the valve equals that of the eccentric, the distance from the center of the eccentric to the center of its pivot equals the 65 distance from the center of the pivot to the center of the shaft, less the combined lap and lead of the valve. If the arm 3 be so located that the center line of the eccentric is in line with the axes of the crank-shaft and of its pivot, the 70 movement of the valve will be coincident with but in opposite direction from that of the piston, and will be only of sufficient extent to uncover the steam-port at the induction for the amount determined as the minimum lead, which should not be sufficient to run the unloaded engine up to speed. Movement of the eccentric-arm from this position in either direction will increase the radius of eccentricity and consequently the travel of 75 the valve, change the angular position of the eccentric, and effect movement of the engine in a direction contrary to that of the advance of the eccentric. As a result of the increase 80 of movement and of the backward change of angular position of the eccentric the cut-off is effected later in the stroke, while the lead is but slightly changed, the measure of such change being the departure of the segmental path of the center of the eccentric due to its 85 pivotal movement from a straight line at right angles to the crank, and consequently the change of lead will be inversely proportional to the length of the eccentric-arm. The change of lead being to increase with later degrees of 90 cut-off is desirable in compensating for the diminished compression attending delayed 95 100

cut-off, and, further, for the reason that increase of travel necessitates a proportionately increased absolute amount to approximate relative equality.

5 The adjustments of the eccentric 2 toward and from the angular position above specified—to wit, with its center in line with the axes of the shaft and of its pivot 4—are effected by the action of pivoted weights 5 under induced 10 centrifugal force and of centripetally-acting springs 6, respectively. The weights 5 are secured upon the outer ends of weight-arms 7 8, which are pivoted to the wheel 1 at diametrically opposite points in a line perpendicular to the crank, and on opposite sides of said line, by pins or bolts 9, and the weight-arms 7 8 are coupled to the eccentric 2 by links 10, one of which is attached to the weight-arm 7 between the pivot and the 15 weight thereof, and the other to an arm, 11, projecting inwardly from the weight-arm 8, beyond its pivot, the weight-arms 7 8 thus being levers of the second and of the first order, respectively, and, by their outward movements under the influence of centrifugal force, 20 acting conjointly to move the eccentric toward the center of the shaft.

Under the above construction I am enabled to materially enlarge the range of movement 30 of the weight-arms relatively to corresponding mechanism heretofore employed, and thereby to attain close regulation with the employment of centripetally-acting springs of correspondingly reduced initial tension. The traverse of each weight-arm is arrested at the proper inward and outward limits by two stop-pins, 12, formed of or faced with wood or other suitable yielding material, which are fitted in sockets 13 14 on the supporting-wheel 40 1; and to admit of the adjustment of the parts for an opposite direction of rotation of the crank-shaft two supplemental stop-pin sockets, 15 16, are provided for each weight-arm, the sockets 13 14 and 15 16 being located 45 symmetrically on each side of the line joining the centers of the weight-arm pivots. Centripetal force in opposition to the outward movements of the weights 5 is exerted by two plate-springs, 6, secured at one end to a block, 18, pivoted to the wheel 1 adjacent to its periphery, said springs extending inwardly therefrom, and bearing at their opposite ends against a roller, 19, journaled on a pin, 20, on the eccentric, and a roller, 21, on a pin, 50 22, in the wheel 1, adjacent to its hub. The sides of the block 18, which carries the springs 6, are of such taper as to impart to the springs a divergence which will cause them to be straight when not under tension, and by the 55 pivotal connection of the block the two springs receive and impart strain equally. The construction further admits of the springs being removed, slightly set, and reversed, if found not to be sufficiently elastic, so that subsequent flexure may be imparted in an opposite direction. The roller 21 is adjustable toward 60 and from the radial line connecting the cen-

ters of the shaft and of the spring-block pivot, in order to vary the tension of the springs, by a set-screw, 23, engaging a thread in the 70 arm of the wheel which carries the pivot 22 of the roller, and bearing at its inner end on said pivot, which passes through a hole which is slotted or elongated in line with the set-screw 23. The pivot 22 is held firmly in adjusted position by a nut and washer. A supplemental socket, 24, having a similarly-slotted hole, and located on the opposite side of the radius connecting the shaft and spring-block centers, serves to receive the pivot 22 75 when the parts are adjusted for a reverse direction of rotation of the shaft. The reversal is effected by changing the relative position of the weight-arms and turning their opposite sides outward, so that, as in the adjustment first described, their pivot ends lead and their weight ends follow in the rotation of the shaft, and as each weight-arm works on the same side of the line joining the pivot-centers, as before, it will be seen that the 80 supplemental sockets 15 16 are properly located to receive the stop-pins. The roller 21 is also similarly adjustable in the supplemental socket 24. The gravity of the eccentric 2 is balanced by a counter-weight, 95 25, on an arm, 26, fixed on the eccentric-pivot 4 and projecting through an opening, 27, in the bearing 28 thereof, which is outwardly inclined or tapered to admit of the traverse of the arm resultant on the adjustments of the eccentric. It has been found in practice that the best results are obtained when the effective amount of the counter-weight is somewhat less than that required for a complete gravity-balance, for the following reason:

In governors of this class, in which a valve opposing a certain amount of resistance is to be actuated, a certain degree of friction is desirable of that character which opposes adjustment in either direction, and which may be termed "static friction," in contradistinction to the friction of the actuated parts, which, tending to produce a change of adjustment in a particular direction, may be called "dynamic friction." The static friction is in 100 proper degree when it is just sufficient to prevent the dynamic resistance from sensibly disturbing the equilibrium of the governor, yet not sufficient to prevent such minute degree of disturbance as will, by frequently overcoming the static friction in a slight degree, cause its action to be as sensitive to minute changes of load and pressure as though the parts were 105 without friction. The counter-weight 25, in addition to acting as a gravity-balance, also 110 exerts centrifugal force, which augments the static friction of the eccentric-pivot 4 in its bearing, and in some cases such augmentation of friction may be sufficient to make it in excess, and thereby to produce sluggishness of 115 action. In such case, if the effectiveness of the counter-weight be diminished, which is provided for by mounting it adjustably and 120 removably upon its arm 26 and securing it 125 130

thereto by a set-screw, 29, so that it may be shifted inwardly or be removed and replaced by a lighter counter-weight, the friction induced by its centrifugal force will be reduced, 5 and the correspondingly unbalanced weight of the eccentric will cause an equivalent increase in the dynamic tendencies, so that by the adjustment of the weight upon the arm a point may be reached at which the static and 10 dynamic tendencies will be in such relation one to the other as to enable the greatest practicable degree of sensitiveness consistent with sufficient stability of equilibrium to be attained. Such adjustment will vary for different 15 speeds, so that to enable the engine to be properly regulated for any desired speed the adjustability of the counter-weight becomes of substantial value and importance.

I claim as my invention and desire to secure 20 by Letters Patent—

1. In a steam-engine governor, the combination, substantially as set forth, of a supporting wheel or disk, a valve-operating eccentric pivoted thereto, two weighted arms 25 pivoted to the supporting-wheel at points in a line perpendicular to the line joining the centers of said wheel and of the eccentric-pivot, and adapted to move about their pivots on opposite sides of the line joining the 30 same, links coupling the eccentric with the weight-arms, and connected to the latter on opposite sides, respectively, of their pivots, and a pair of plate-springs connected at one end to the supporting-wheel at a point substantially in line with the centers of said wheel 35 and of the eccentric-pivot, and abutting at the other against stops on the wheel and on the eccentric, respectively.

2. In a steam-engine governor, the combination, substantially as set forth, of a supporting wheel or disk, a valve-operating eccentric pivoted thereto, weighted arms pivoted 40 to said wheel and adapted to be relatively reversed in position thereon, links connecting 45 said arms with the eccentric, stop-pin sockets located in pairs on opposite sides of a diametric line connecting the weight-arm pivots, a pair of stop-pins for each weight-arm, adapted 50 to fit in the sockets on either side of said line, a spring-stop adapted to fit in either of two

sockets adjacent to the eccentric, and on opposite sides of a line perpendicular to the line joining the weight-arm pivots, and springs connected to the supporting-wheel and bearing against said stop and against a stop on the 55 eccentric.

3. In a steam-engine governor, the combination, substantially as set forth, of a supporting wheel or disk, a valve-operating eccentric pivoted thereto, weighted arms pivoted to said wheel and coupled to the eccentric, a spring-block pivoted to the supporting-wheel, and having its sides tapered or inclined toward the periphery thereof, and a pair of plate-springs secured to the sides of the 60 spring-block, and adapted to bear against stops on the supporting-wheel and the eccentric, respectively.

4. In a steam-engine governor, the combination, substantially as set forth, of a supporting wheel or disk, a valve-operating eccentric pivoted thereto, a counter-weight connected adjustably to said eccentric, and weights and springs acting to vary the position of said eccentric by the exertion of centrifugal and 70 centripetal force, respectively, thereon.

5. In a steam-engine governor, the combination, substantially as set forth, of a supporting wheel or disk, a valve-operating eccentric pivoted thereto, weighted arms pivoted to the supporting-wheel and coupled to the eccentric, an adjustable spring-stop connected to said wheel, and springs secured at one end to said wheel and bearing at the other 80 against said adjustable stop and against a stop 85 on the eccentric.

6. In a steam-engine governor, the combination, substantially as set forth, of a spring-block having inclined or tapered sides and an opening for a pivot by which it may be 90 secured to the supporting wheel or case of the governor, and a pair of flat plate springs connected to the sides of the spring-block, these members being combined for joint operation to admit of the reversal and setting of the 95 springs.
